UNITED STATES PATENT OFFICE.

SIMON BERRY, OF SEATTLE, WASHINGTON.

METHOD OF AND APPARATUS FOR MOLDING BUILDING BLOCKS.

Application filed April 25, 1928. Serial No. 272,586.

My invention relates to molds intended for the production of perforated blocks, such for instance as are largely used for constructing partition walls.

5 The object of my invention is to produce a more perfect block while reducing the time and labor required and to provide a mechanism for doing this which will enable a workman to turn out an increased product.

10 In the accompanying drawings I have illustrated a mechanism which may be used to secure the above mentioned results.

Figure 1 is a plan view of the assembled apparatus employed, different compartments 15 of the mold being shown in different conditions.

Figure 2 is an end elevation and partial section of the same.

Figure 3 is a cross sectional elevation taken 20 on a plane at right angles to that of Figure 2.

Figure 4 is a plan view of a portion of the molds illustrating steps in the making of the blocks.

The type of block produced by the practice 25 of my invention is in its most common embodiment in the form of a rectangular slab having holes therethrough extending from one edge to the opposite edge and parallel to the main side faces. These holes are usually 30 circular cross section, although they may be made of other cross section. I have illustrated the usual type of block.

I prefer to assemble the molds in groups or batteries, which will mold at the same time a 35 number of blocks. The apparatus shown will mold at one time sixteen blocks. The number may be varied. The apparatus illustrated has four compartments, each forming four blocks, 1.

40 The walls of each compartment is formed by two side bars 2, connected towards their ends by transverse bars 20. The end bars 20 should be securely held in proper position, as by the use of tongue and groove joints, as 45 has been illustrated. The outermost side bar 2 of a group may be supported against outward thrust by brackets or buttresses 21.

Each compartment is divided into a series of block molds by transverse partition plates 50 22, their ends entering grooves in the side bars 2. The cross bars 20 and partition plate 22 all have holes for the reception of the core rods 3. The bottom or floor of each compartment is preferably composed of a metal plate 55 4, having one end turned up to form a flange 43, perforated to receive the core bars. A lin-

ing or surface forming sheet 40 may be placed upon plate 4, and this sheet may have a grooved or otherwise shaped upper surface which will produce a like surface upon the 60 block. A cover plate or sheet 41 may similarly be used to give the upper surface of the block such pattern as may be desired. This latter sheet must be pressed or forced down upon the block material while it is still plastic. 65

For convenience of handling, the bars 2 and 20 are preferably made deeper than the block to be made, so that the metal bottom plates 4 may be provided with supporting 70 wheels 42.

The core bars 3 are not tapered, but are of uniform size throughout their length. At one end they are engaged by a mechanism by which they may be given such movement 75 while the blocks are setting as will prevent the block from gripping the rods. This movement may be a reciprocating or a rotary turning movement, or a combination of both. The device illustrated will produce the combined movement. 80

A bar 5 is fixed alongside of the battery of molds and has guides for each core bar. Such guides and the end of the core bar may be of complementary helical thread or screw 85 like construction, 50, so that reciprocation of the rods will also cause a rotative or turning movement.

The core bars 3 are connected with a cross-head bar 6 and this is connected by connecting rods 60 with crank pins 61, carried by a shaft 62, which shaft is slowly turned in any convenient and suitable manner, as through a worm and gear mechanism 63, by a motor 64. It is the purpose by this or an equivalent 90 mechanism, to give the core bars a slow movement relative to the block being molded, thereby to prevent binding of the block upon the bars. By doing this it is possible to use core bars without any taper, from which it 95 follows that the holes in the blocks may all be of the same size and of true shape and the size and spacing of the holes to be such as to make the maximum of voids without reducing the thickness of the walls below the contemplated minimum. It also makes possible molding at one time a considerable series of blocks upon the same core bars, thereby increasing the output. The method employed is also such as will reduce to a minimum 100 breakage caused by removal of core bars. 110

The manner of operation is as follows: The

parts of the mold are assembled in their proper relation, which relation has hereinbefore been described, whereupon the block compartments are filled with the material of 5 which the block is made, this being in a plastic condition. The motor should be in operation and the core bars being reciprocated. This reciprocation of the bars should continue through what I call the preliminary 10 setting of the block material. By this is meant setting to such a point that the block has enough permanency of condition to retain its shape when the core bars are withdrawn.

15 When this condition of setting has been reached, or any time thereafter which is convenient, the mold is disassembled to the point where the bottom plates 4 of the respective compartments may be drawn out. This 20 may be done if the side bars 2 are lifted. As the plate 4 is drawn out the blocks thereon are drawn off of the core bars after which the partition plates 22 may be removed.

When drawing out the plates 4 the blocks 25 1 thereon are positively supported by the flanges 43 of the plate, to thereby be forced off of the core bars. Blocks molded in this manner and by the use of the apparatus described will be true and uniform in all their 30 dimensions, including thickness of walls. The ability to do this makes it possible to

make the walls thinner than would be possible where variation of sizes necessitates extra allowance of thickness. In consequence, a saving of weight and material is possible. 35

The material most commonly used in making such building blocks is a gypsum compound. This sets very quickly so that but a few minutes need elapse before sufficient setting has occurred to permit removal of the 40 cores. Any other material or compound found to be adapted to this work may be employed.

What I claim as my invention is:

1. The method of molding perforated blocks of cementitious material by the use of cores which consists in giving the cores a movement during the preliminary setting period which is a compound of reciprocative and rotary movements. 45

2. An apparatus for molding perforated blocks comprising a mold adapted to outline the blocks, core bars extending through said mold, fixed guide members for the core bars, said core bars and guide members having interengaging screw surfaces adapted upon reciprocation of the core bars to also give them a turning movement, and means for reciprocating the core bars. 50 55

Signed at Seattle, King county, Washington, this 19th day of April, 1928.

SIMON BERRY.
